[57] CLAIM

The ornamental design for a pager with clip and container attachment, as shown and described.

DESCRIPTION

FIG. 1 is a perspective view of a pager with clip and container attachment showing my new design, the broken line showing of the spray bottle housed in the container is for illustrative purposes only and forms no part of the claimed design;

FIG. 2 is a perspective view thereof, wherein the container attachment is removed from the pager, shown separately for clarity of illustration;

FIG. 3 is a front elevational view of FIG. 1;

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.
